UNITED STATES PATENT OFFICE

2,089,551

SEWING MACHINE MECHANISM

John F. Hand, Philadelphia, Pa., assignor to
 The De Long Hook and Eye Company, a corporation of Pennsylvania

Application November 10, 1934, Serial No. 752,441

22 Claims. (Cl. 112—2)

The invention relates to sewing machine mechanism and involves various improvements for the purpose of adapting such mechanism for sewing eyelet tape or the like to strips or pieces of fabric.

The invention has for one of its principal objects the provision of a pocket for the eyelets, formed between the eyelet tape and the goods to which the tape is secured and having one side thereof open in order to give access to the eyelets. This object is accomplished by the provision of mechanism for stitching the eyelet tape to the goods lengthwise of the tape and in line with the eyelets, and deflecting the line of stitching inwardly from one edge of the tape around each of the eyelets as they are successively reached in the stitching operation.

The invention has for a further object the provision of improved mechanism for deflecting the line of stitching around the eyelets during the process of securing the eyelet tape to a strip of fabric. This object is accomplished by employing a reciprocating needle bar mounted for swinging movement transversely of the direction of feed of the goods, and by providing improved mechanism for swinging the needle bar, the operation of which is initiated by means of a feeler device arranged to be actuated by engagement with the successive eyelets.

A further object of the invention is the provision of mechanism for varying the speed of the work feeding device during the formation of the eyelet pockets. This object is accomplished by the provision of speed varying mechanism the operation of which is initiated likewise by the engagement of a feeler device with the eyelets as the successive eyelets approach the stitch forming mechanism.

Another object of the invention is the provision of improved mechanism for transmitting power from the main drive shaft of the sewing machine to the actuating mechanism for the speed varying device and the needle bar swinging device.

A still further object of the invention is the provision of improved mechanism for varying the speed of the work feeding device associated with the stitch forming mechanism of a sewing machine.

A further object of the invention is the provision of an improved feeler device for cooperation with the successive eyelets of eyelet tape in order to initiate the actuation of the speed changing mechanism of the work feeding device and the actuation of the needle bar swinging

mechanism as the successive eyelets approach the stitch forming mechanism.

A further object of the invention is the provision of an improved feeler or tripping device which is so constructed that it will operate by engagement with the eyelets and will not be operated by engagement with an increased thickness of the goods, such as a seam.

A still further object of the invention is the provision of an improved structure for feeding the work so as to enable the entire length of the strip of eyelet tape or the like and of the fabric to be stitched together. This object is accomplished by the provision of a work feed structure wherein the work is advanced past the stitch forming mechanism by means of a carrier tape acting in cooperation with a pair of feed rolls positioned in the rear of the stitch forming mechanism.

Still further objects and advantages of the various features of the invention will be apparent from the following description, taken with the accompanying drawings wherein:

Fig. 1 is a perspective view of a sewing machine mechanism with the present improvements incorporated therein;

Fig. 2 is a front elevational view thereof, with parts omitted or broken away;

Fig. 3 is an elevational view of the end of the machine with which the stitch forming mechanism is associated;

Fig. 4 is a horizontal, longitudinal, sectional view of the machine taken on the line 4—4 of Fig. 2;

Fig. 5 is a longitudinal, sectional view taken on the line 5—5 of Fig. 4;

Fig. 6 is a vertical, sectional view taken on the line 6—6 of Fig. 2;

Fig. 7 is a vertical, sectional view taken on the line 7—7 of Fig. 5;

Fig. 8 is an enlarged, sectional view taken on the line 8—8 of Fig. 4, and showing details of the transmission mechanism between the main drive shaft and the cam shaft for controlling the speed of the work feeding device and the swinging action of the needle bar;

Fig. 9 is a view similar to Fig. 8, showing the parts in a different position;

Fig. 10 is a plan view, partly in section, of the transmission mechanism shown in Fig. 8;

Fig. 11 is a sectional view taken on the line 11—11 of Fig. 8;

Fig. 12 is a rear, elevational view of a portion of the speed varying mechanism of the work feeding device;

- Fig. 13 is a transverse, sectional view taken on the line 13—13 of Fig. 4, and showing one position of the adjustable eccentric forming part of the work feeding mechanism;
- 5 Fig. 14 is a view similar to Fig. 13 showing another position of the adjustable eccentric;
- Fig. 15 is a detailed, elevational view showing the contour of the cam employed for swinging the needle bar;
- 10 Fig. 16 is a detailed, elevational view showing the contour of the cam employed for controlling the speed of the work feeding mechanism;
- Fig. 17 is an enlarged, transverse, sectional view taken on the line 17—17 of Fig. 4;
- 15 Fig. 18 is a transverse, sectional view taken on the line 18—18 of Fig. 17;
- Fig. 19 is a transverse, sectional view taken on the line 19—19 of Fig. 17;
- 20 Fig. 20 is an enlarged, plan view showing a section of a strip of eyelet tape stitched to a strip of fabric by the improved mechanism disclosed herein;
- Fig. 21 is a transverse, sectional view of the same; and
- 25 Fig. 22 is a transverse, sectional view similar to Fig. 21 but showing the strip of fabric folded upon and stitched to itself and to the eyelet tape in position to be attached to a piece of fabric material.
- 30 The various features of the present invention, as illustrated in the drawings, are incorporated in a sewing machine having the usual bed plate 1 and bracket arm 2 supported thereon, the bracket arm having a head 3 on the free end thereof within which the reciprocating needle bar 4 is mounted, the needle 5 being secured within the lower end of the needle bar. In the machine disclosed herein, the needle bar 4 is mounted to reciprocate longitudinally in guideways 6 formed in a swinging arm 7 pivoted at its upper end to the head 3, as shown at 8, and provided with a pin and slot structure 9 near the lower end thereof for guiding the arm in its swinging movement with respect to the head.
- 45 The main drive shaft 10 extends through the horizontal portion of the bracket arm 2 and is mounted for rotation in suitable bearings in the bracket arm. The drive shaft 10 is rotated by means of a belt 11 passing over a pulley 12 secured on the outwardly projecting end of the shaft, the belt being driven from any suitable source of power, such as an electric motor. The end of the drive shaft adjacent the head 3 of the bracket arm may be provided with any well known means, such as a pitman structure 13, for imparting reciprocatory movement to the needle bar 4.
- Extending longitudinally beneath the bed plate 1 and supported in suitable bearings 14 on the bed plate is a shaft 15 having a pulley 16 secured on one end thereof and driven by a belt 17 passing around a pulley 18 secured on the main drive shaft. The opposite end of the shaft 15 terminates beneath the head 3 and is provided with a bevel gear 19 which meshes with a bevel gear 20 secured on a stub shaft 21 supported in a bearing member 22 on the bed plate. Secured on the free end of the stub shaft 21 is a rotary hook or looping device 23 of usual structure for cooperation with the needle 5 to provide stitch forming mechanism.
- Supported in suitable brackets 24 projecting rearwardly from the bed plate 1 is a feed shaft 25 having a feed roll 26 secured thereon in co-

operative relation to a pressure roll 27 supported above the feed roll for movement toward and away from the latter. As illustrated herein, the pressure roll 27 is supported in a bracket 28 carried upon the lower end of a rod 29 supported for vertical movement in a bracket 30 mounted upon the head 3 and extending rearwardly thereof. The rod 29 is pressed downwardly by means of a coiled spring 31 surrounding the same and having the lower end in engagement with a collar 32 secured to the rod and the upper end in engagement with the lower end of a hollow adjusting screw 33 through which the rod extends. A manipulating handle 34 of well known form may be pivoted to the supporting bracket 30 for lifting the pressure roll 27 out of engagement with the feed roll 26, this handle being provided with a flattened portion 35 for engagement beneath a projection 36 on the collar 32 in order to hold the pressure roll in its raised position.

The extended end of the feed shaft 25 may be provided with a milled knob 37 for manual rotation of the shaft at any time desired. The feed shaft is preferably provided with a brake structure 38 having a manually adjustable braking action and operating continuously in order that the step-by-step rotation of the shaft may be properly controlled. Step-by-step motion is imparted to the feed shaft by means of a ratchet wheel 39 secured thereon for cooperation with a pawl 40.

As shown in Figs. 3, 4 and 6, the pawl 40 is pivoted to the outer end of the arm 41 of a two-armed lever 42 loosely mounted on the feed shaft 25, and this arm has secured thereto a flat spring 43 a portion of which engages with the pawl 40 for the purpose of keeping the pawl in contact with the ratchet wheel 39. From the free end of the other arm 44 of the two-armed lever 42 a link 45 extends to the free end of a crank arm 46 adjustably secured on a rock shaft 47 extending longitudinally beneath the bed plate 1 and suitably supported in bearings 48 projecting therefrom. The rock shaft 47 receives its rocking movement through a crank arm 49 adjustably secured thereon and having its free end pivotally connected to the lower end of an eccentric rod 50 the upper end of which is provided with an eccentric strap 51 surrounding an eccentric 52 adjustably secured to one face of the pulley 18 on the main drive shaft 10.

Referring to Figs. 4, 5, 13 and 14, it will be noted that the eccentric 52 has an enlarged opening 53 therethrough for receiving the shaft 10, and is provided with an enlarged hub having a pair of diametrically arranged ears 54, 55 thereon. The ear 54 is pivoted upon the adjacent face of the pulley 18 by means of a screw 56 passing freely through the ear and threaded into an opening in the pulley. The ear 55 is provided with an elongated slot 57 for loosely receiving a screw 58 which is threaded in a suitable opening in the adjacent face of the pulley 18. This pin and slot arrangement serves as a guide for the ear 55 thereby permitting the eccentric to swing upon the screw 56 into different positions of eccentricity with respect to shaft 10.

Arranged substantially at right angles to the ears 54, 55 and extending outwardly from the hub of the eccentric 52 is a pair of hollow projections 59, 60. Hollow projection 59 is threaded for the reception of a screw 61 having a pin 62 extending from the inner end thereof through an opening 63 in the wall of the drive shaft 10 and communicating with a bore 64 extending in-

wardly from the end of the drive shaft 10 as shown in Fig. 4. A pin 65 having its inner end in engagement with the drive shaft 10 is slidably mounted in the hollow projection 60, and is 5 pressed inwardly and retained in contact with the drive shaft by means of a coiled spring 66 the tension of which may be adjusted by means of a screw 67 threaded in the outer end of the projection 60.

10 The eccentric 62 is automatically adjusted into different positions of eccentricity with respect to the drive shaft 10 by means of a bolt 68 extending into the bore 64 in the end of the drive shaft and having its inner end 69 tapered for cooperation with the inner end of the pin 62. With such a structure it will be apparent that movement of the bolt 68 inwardly within the bore of the drive shaft will bring the tapered inner end thereof into engagement with the pin 62 and thus swing the eccentric against the tension of the spring 66 and about the screw 66 so that the eccentric may be adjusted into various positions to increase its eccentricity with respect to the drive shaft. It will also be apparent that when 25 bolt 68 is moved outwardly in the bore 64 spring 66 will operate to shift the eccentric in the opposite direction to thereby decrease the eccentricity from maximum as shown in Fig. 13 to minimum or zero eccentricity as shown in Fig. 14.

30 As shown in Figs. 4, 5 and 12, the outer end of the eccentric adjusting bolt 68 is threaded in a frame 70 which is mounted for reciprocating movement in a guideway 71 secured on the rear of the bracket arm 2. The inner end of the frame 35 70 is provided with an offset portion 72 having a cam roller 73 thereon for cooperation with a cam 74 for varying the feed of the work and herein-after referred to as the feed cam. The roller 73 is kept in engagement with the feed cam by means 40 of a coiled spring 75 one end of which is secured to a pin 76 fixed to the frame 70 and the opposite end of which is secured to a pin 77 fixed to the guideway 71.

45 The feed cam 74 is secured on the rear end of a cam shaft 78 extending from front to rear through the bracket arm 2 and provided with a milled knob 79 for effecting manual adjustment thereof and of the cams carried thereby. In order to control the rotation of the cam shaft 78, a 50 braking device 76 may be provided therefor in the rear of the bracket arm 2. A cam 80 for swinging the needle bar 4, and herein-after referred to as the needle cam, is secured on the cam shaft 78 in front of the bracket arm 2. The 55 needle cam 80 cooperates with a cam roller 81 on the end of a cam rod 82 having a slot 83 therein for engagement with the cam shaft 78 to guide the cam rod in its reciprocating movement. Cam roller 81 is kept in engagement with the needle 60 cam 80 by means of a coiled spring 84 one end of which is secured to a pin 85 fixed to cam rod 82 and the opposite end of which is fixed to a pin 86 suitably supported upon the bracket arm 2. The end of the cam rod 82 opposite the cam 65 roller 81 is pivoted to the lower end of the swinging arm 7 upon which the needle bar 4 is mounted. It will be apparent, therefore, that rotation of needle cam 80 will operate to swing the arm 7 about its pivot 8 and thereby oscillate or swing 70 the needle 5 transversely of the direction in which the needle reciprocates during the stitch forming operation.

75 In the form in which the invention is disclosed herein, both the feed cam 74 and the needle cam 80 are stationary when the machine is operating

to form a straight line of stitches in the direction of feed of the goods. In order to discontinue the operation of the feed mechanism or vary the rate of feed of the goods, and in order to provide a swinging movement of the needle bar 4 when an 5 eyelet or the like approaches the needle 5, a novel form of mechanism has been provided for rotating the cam shaft 78 step by step, this operation being initiated by engagement of the eyelets with a part of the mechanism.

10 Referring to Figs. 5, 6, 8, 9 and 10, it will be noted that a ratchet wheel 87 is secured on the cam shaft 78 beneath the drive shaft 10, and a pawl 88 having its free end arranged for cooperation with the teeth of the ratchet wheel 87 has 15 its opposite end pivoted to the arm 89 of a two-armed lever 90 loosely supported on the cam shaft 78. A coiled spring 91 having one end secured to a pin 92 fixed to the pawl 88 and the opposite end secured to the two-armed lever 90 20 serves to pull the free end of the pawl 88 toward the ratchet wheel. The other arm 93 of the lever 90 projects upwardly and is provided with a cam roller 94 which engages with a cam slot 95 formed in a cam cylinder 96 secured on the drive shaft 25 10 and rotating continuously therewith.

25 Inasmuch as the pawl 88 is continuously reciprocated during the operation of the machine, means have been provided for keeping it out of engagement with the ratchet wheel 87 except at 30 such times as the speed varying mechanism is to be actuated and the needle bar is to be oscillated transversely of the direction of its reciprocating movement. The pawl 88 is normally retained in inoperative relation with respect to the ratchet 35 wheel 87 by means of a detent 97 pivoted on the ratchet wheel as shown at 98. A coiled spring 99 having one end secured to the detent 97 and its opposite end secured to a pin 100 fixed to the ratchet wheel 87 operates to move the edge 101 of 40 the detent into the position shown in Fig. 8 wherein the pawl 88 slides back and forth upon the edge 101 and therefore does not operate to rotate cam shaft 78 during its reciprocating movement.

45 In order that the detent 97 may be moved into a position to permit pawl 88 to engage with the teeth of the ratchet wheel 87, a lug 102 is provided on the upper end of a trip rod 103 having a longitudinal slot 104 therein for engagement about cam shaft 78 to guide the rod in its vertical movements. The lug 102 is arranged to engage with a pin 105 projecting outwardly from one face of the detent 97 as will be clear from Figs. 6 and 11. The lower end of trip rod 103 is 50 pivoted to one end of a trip lever 106 the opposite end of which is adjustably secured on a rock shaft 107 by means of a set screw 108. The trip rod 103, together with the trip lever 106, is held in its uppermost position by means of a coiled spring 109 having its lower end secured to the trip lever 55 and its upper end secured to a fixed pin 110. Movement of the trip lever 106 upwardly is limited by means of an adjustable screw 111 threaded through the free end of a bracket 112 60 secured to the bed plate 1. Movement of the trip lever 106 downwardly is limited by means of an adjustable screw 113 65 threaded through the free end of a bracket 114 secured to the bed plate 1.

70 The rock shaft 107 is mounted transversely of the bed plate 1 alongside the stitch forming mechanism and is supported in suitable bearings 115 secured to and projecting upwardly from the bed plate. Adjustably secured on the rock shaft 107, as by a set screw 116 and milled nuts 117 threaded on the rock shaft, is a feeler arm 118 the outer end of which is so positioned as to constitute a feeler 119 for engagement by eye- 75

lets or the like as they approach the stitch forming mechanism during the operation of the machine. Preferably, the arm 116 is so constructed that the feeler may be adjusted to and from the rock shaft 107 as shown at 118.

The feeler 117 is spring pressed toward the work by means of a tensioning member comprising a lever arm 119 adjustably secured to the rock shaft 107 by a set screw 120 and projecting from the rock shaft in a direction opposite to the feeler arm 116. The free end of the lever arm 119 is provided with a boss 121 having a vertical opening therethrough within which the upper end of a pin 122 is slidably received. A coiled spring 123 surrounds the pin 122 between the boss 121 and the head of the pin. It will be apparent that by loosening the set screw 120 the lever arm 119 may be adjusted radially about the rock shaft 107 to thereby vary the tension in the coiled spring 123 and consequently vary the pressure of the feeler 117 upon the goods. This structure provides a simple means for adjusting the position of the feeler with respect to the goods, so that the tripping device will be operated by engagement of the feeler with the successive eyelets or the like and will not be operated by its engagement with an unusual thickness of the fabric material, such as seams.

The feeler 117 is so arranged as to project downwardly into a slot formed by the opposing edges of a retainer plate 124 and a movable guide bar 125, as illustrated in Figs. 1, 4, 5 and 19. The retainer plate 124 has one edge thereof projecting outwardly beyond a spacer member 126 to which the opposite edge of the plate is secured. The inner edge of the movable guide bar 125 is cut away to provide a shoulder 127 which forms a guide for one edge of the eyelet tape T, and to provide an overhanging portion 128 for retaining the eyelet tape T in position as it moves inwardly with the material M toward the stitch forming mechanism. As shown in Figs. 18 and 19, the spacer 126 forms a guide for the opposite edge of the eyelet tape and the adjacent edge of the material to which the tape is being secured.

The guide bar 125 is provided with a pair of spaced ears 129 one of which is secured to the free end of an arm 130 pivoted to a bearing member 131 secured to and extending upwardly from the retainer plate 124, the other being secured to one end of a lever 132 pivoted to a bearing member 133 projecting upwardly from the retainer plate. The opposite end of lever 132 is bent into a position outwardly of the forward edge of the bed plate 1, and by means of a chain 134 or the like may be connected to a pedal so that the guide bar may be lifted out of contact with the work. A spring 135 with one end secured to the bed plate 1 may be so bent as to have its opposite end engage with the lever 132 for the purpose of holding the guide bar 125 in contact with the work.

Referring to Figs. 3, 5 and 17, it will be noted that the bed plate 1 is cut away adjacent the stitch forming mechanism, and the opening thus formed is provided with an insert 136 having an elongated slot 137 therein to receive the needle 5 and permit the same to swing laterally for the purpose of stitching around the eyelets U. The needle slot 137 registers with a similar slot in a wear plate 138 secured to the upper face of the bed plate. The insert 136 and the wear plate 138 are also provided with registering slots slightly in advance of the needle slot in order to form an outlet 139 for a carrier tape W utilized in feeding the work in the present mechanism. The

carrier tape W passes rearwardly from the front edge of the bed plate 1 through a channel 140 formed on the upper face of the bed plate and covered by the wear plate 138. When the carrier tape W emerges from the opening 139 it comes into engagement with the fabric material M to which the eyelet tape T is being secured, and after being secured together by the stitch forming mechanism the eyelet tape, the fabric material and the carrier tape are advanced as a unit by the work feed device heretofore described.

In machines of this general character the work feed device is conveniently arranged at the rear of the bed plate 1, in line with the stitch forming mechanism. The use of a carrier tape in the manner disclosed herein provides a simple means for feeding the goods through the machine and is particularly useful in providing a feed for the initial portion of the goods as they approach the stitch forming mechanism and move from the stitch forming mechanism to the feed device. Such a carrier tape is also advantageous by reason of the fact that the goods or pieces of material to which the eyelet tape is secured are usually of limited length so that the carrier tape provides a means whereby the goods may be continuously fed past the stitch forming mechanism notwithstanding the short lengths of material which are utilized.

As the invention is illustrated herein, the parts thereof are so designed and are so timed with respect to each other as to form a line of stitching S lengthwise of the eyelet tape T, with three tie-stitches a, b, c connecting the line of stitching S with the stitches d, e, f, g, h, i deflected around the eyelets U and connected, in turn, to the line of stitching S by the three tie-stitches j, k, l. In order to form this series of stitches the needle cam 80 is so designed as to provide operating portions a' to l' as shown in Fig. 15 of the drawings, these portions corresponding respectively to stitches a to l shown in Fig. 20.

The needle cam 80 is illustrated in Figs. 1, 2 and 15 of the drawings in a position in which the cam roller 81 occupies a low point thereon, and the needle bar 4 is thus in a position wherein it reciprocates vertically without being subjected to a simultaneous swinging movement. When an eyelet U comes into engagement with the feeler 117 of the trip mechanism to thereby move the detent 97 into a position wherein the pawl 88 may cooperate with the teeth of the ratchet wheel 87, the cam shaft 78 is rotated step by step through a complete cycle of its operation by reason of the continuous reciprocatory movement of the pawl 88. It will be noted that the ratchet wheel 87 is provided with twelve teeth, the number thus employed to complete its operative cycle corresponding with the number of stitches employed in stitching around each eyelet, and with the number of portions into which the operating face of the needle cam is divided.

The first movement of the needle cam 80 from the position shown in Fig. 15, and in the direction of the arrow shown therein, operates to move the cam roller 81 up the inclined portion a' to thereby swing the needle bar to the right (referring to Fig. 2) to produce the tie-stitch a. During the next movement of the cam 80 the cam roller 81 rides inwardly on the inclined portion b' during which time the tie-stitch b is formed. During the next movement of the cam 80 the cam roller 81 rides upwardly on the inclined portion c' to again swing the needle bar 70

to the right and form stitch *c*. During the next succeeding movement of cam 80 cam roller 81 rides upwardly along the inclined face *d'*, thereby swinging the needle bar still further to the right to produce the stitch *d*. In the next succeeding movement of cam 80 cam roller 81 continues upwardly on the inclined face *e'* and the needle bar is swung still further to the right to produce the stitch *e*. During the next two succeeding movements of cam 80 cam roller 81 traverses the portions *f', g'* of cam 80 and, inasmuch as these portions are arranged to effect no cam action, the two stitches *f, g* will be formed parallel to the line of stitching *S*. During the next movement of cam 80 cam roller 81 rides inwardly along the inclined portion *h'* thereby permitting the needle bar to swing to the left and produce the stitch *h*. In the next movement of cam 80 cam roller 81 rides still further inwardly on the portion *i'* to produce the stitch *i*. In the next succeeding movement of cam 80 cam roller 81 rides inwardly along the abruptly inclined portion *j'* to produce the tie-stitch *j*. In the next movement of cam 80 cam roller 81 rides upwardly upon the inclined portion *k'* to again move the needle bar to the right and produce the tie-stitch *k*. In the final movement of the cam the cam roller rides inwardly along the inclined portion *l'* to produce the tie-stitch *l* connecting with the line of stitching *S* and completing one cycle of operation of the needle cam.

In order that the feed of the work may be controlled to enable the various stitches to be formed, the surface of the feed cam 74 is likewise designed to provide portions *a''* to *l''* corresponding respectively to the stitches *a* to *l* and to the portions *a'* to *l'* of the needle cam 80. As illustrated in Figs. 4, 12 and 16 of the drawings, the feed cam 74 is in a position in which the adjusting bolt 68 is in its extreme inward position to thereby provide maximum eccentricity of the eccentric 52 as shown in Fig. 13. As will be apparent, when the feed cam is in this position the feed device will operate in a normal way to move the goods past the stitch forming mechanism at a uniform rate.

When an eyelet is advanced into engagement with the feeler 117 to thereby operate the tripping mechanism and initiate the rotation of the cam shaft 78, the first movement of the feed cam 74 in the direction of the arrow as shown in Fig. 16 permits the cam roller 73 to ride down along the inclined portion *a''* and this movement of the cam roller 73 permits the eccentric adjusting bolt 68 to move outwardly under the influence of coiled spring 75 to thereby adjust the eccentric 52 into the position shown in Fig. 14, and thereby discontinue the feed of the work. During the next two consecutive movements of cam 74 cam roller 73 traverses the portions *b''* and *c''* of cam 74, during which time the feed device remains inoperative. In the next movement of cam 74 cam roller 73 rides upwardly on the inclined portion *d''* thereby adjusting the eccentric 52 into a position to operate the feed device to form the stitch *d*. During the next five succeeding movements of cam 74 cam roller 73 traverses the portions *e'', f'', g'', h'', i''* of cam 74, thereby retaining the eccentric 52 in such a position as to continue the operation of the feed device and advance the goods during the formation of the stitches *e* to *i*. In the next three succeeding movements of cam 74 cam roller 73 traverses the low portions *j'', k'', l''* to thereby discontinue the operation of the feed device during

the formation of the tie-strokes *j, k, l*. This completes the cycle of operation of the feed cam 74 and returns the cam roller 73 to the position shown in Fig. 16 wherein normal operation of the feed device takes place for the continued formation of the line of stitching *S* until the trip mechanism is again actuated by an eyelet *U* to initiate the rotation of the cam shaft 78.

With the improvements disclosed herein, it will be apparent that the mechanism operates automatically to deflect the line of stitching around the successive eyelets as they reach the stitch forming mechanism. Inasmuch as the swinging movement of the needle bar and the variation in the feed of the work are controlled by the engagement of a part of the trip mechanism with the particular eyelet adjacent the stitch forming mechanism, the tie strokes and the strokes deflected around the eyelets are properly formed notwithstanding irregularities in the spacing of the eyelets. The improvements have been disclosed herein in connection with mechanism adapted particularly for securing eyelet tape to strips of fabric and the like. It will be apparent, however, that the novel features are equally adaptable for deflecting a line of stitching around other forms of fastener elements such as hooks and eyes.

It will also be apparent that the invention may be employed in securing fastener tape to a strip of fabric without the formation of pockets of the precise type illustrated in Figs. 20, 21 and 22. It will likewise be understood that the improved mechanism disclosed herein may be readily adapted to stitch around eyelets or the like without employing the precise form of stitches which have been disclosed. With the form and arrangement of the various elements illustrated herein, it will be readily apparent to those skilled in the art that other forms and arrangements of the tie strokes and deflected strokes may be provided by suitably changing the contour of the needle cam and the feed cam, by the provision of the required number of teeth upon the ratchet wheel 87, and by properly timing these and other elements of the mechanism. It will also be apparent that various features of the improvements are readily adaptable for use in combinations and arrangements other than those specifically shown and described herein, and that various changes may be made in the novel combinations, as well as in the elements of the combinations, without departing from the invention which has been made.

The particular features which are believed to be novel and which are intended to be protected by Letters Patent are set out in the following claims:

1. In a sewing machine having feeding means for advancing the work in a given direction, and stitch forming mechanism including a needle bar supported for reciprocatory movement toward and away from the plane of movement of the work and for oscillatory movement transversely of the direction of reciprocatory movement, the combination of means for continuously reciprocating said bar, operating mechanism for simultaneously rendering said feeding means inoperative and oscillating said needle bar, and means in engagement with the work for initiating the actuation of said operating mechanism.

2. In a sewing machine having feeding means for advancing the work in a given direction, and stitch forming mechanism including a needle bar supported for reciprocatory movement toward

- 5 and away from the plane of movement of the work and for oscillatory movement transversely of the direction of reciprocatory movement, the combination of means for continuously reciprocating said bar, operating mechanism for controlling said feeding means and for oscillating said needle bar, and yieldable means in engagement with the work for initiating the actuation of said operating mechanism.

10 3. In a machine for sewing eyelet tape or the like to a strip of fabric and having feeding means for advancing said tape and said strip, and stitch forming mechanism including a needle bar supported for reciprocatory movement toward and away from the work and for oscillatory movement transversely of the direction of reciprocatory movement, the combination of means for continuously reciprocating said bar, operating mechanism for simultaneously rendering said feeding means inoperative and oscillating said bar, and trip means in yielding engagement with the work for initiating the actuation of said operating mechanism by engagement with the eyelets.

15 4. In a machine for sewing eyelet tape or the like to a strip of fabric and having feeding means for advancing said tape and said strip, and stitch forming mechanism including a needle bar supported for reciprocatory movement toward and away from the work and for oscillatory movement transversely of the direction of reciprocatory movement, the combination of means for continuously reciprocating said bar, operating mechanism for controlling said feeding means and for oscillating said bar, and trip means in yielding engagement with the work for initiating the actuation of said operating mechanism by engagement with the eyelets.

20 5. In a sewing machine having feeding means for advancing the work in a given direction, and stitch forming mechanism including a needle bar supported for reciprocatory movement toward and away from the work and for oscillatory movement transversely of the direction of reciprocatory movement, the combination of means for continuously reciprocating said bar, operating mechanism for controlling said feeding means and for oscillating said bar, and trip means in yielding engagement with the work for initiating the actuation of said operating mechanism by engagement with the eyelets.

25 6. In a sewing machine having feeding means for advancing the work in a given direction, and stitch forming mechanism including a needle bar supported for reciprocatory movement toward and away from the work and for oscillatory movement transversely of the direction of reciprocatory movement, the combination of means for continuously reciprocating said bar, operating mechanism for controlling said feeding means and for gradually effecting a single oscillation of said bar simultaneously with 30 a plurality of reciprocatory movements thereof, and means in engagement with the work for initiating the actuation of said operating mechanism.

35 7. In a sewing machine having feeding means for advancing the work in a given direction, and stitch forming mechanism including a needle bar supported for reciprocatory movement toward and away from the work and for oscillatory movement transversely of the direction of reciprocatory movement, the combination of means for continuously reciprocating said bar, operating mechanism for simultaneously varying the speed of said feeding means and oscillating said needle bar, and means 40 in yielding engagement with the work for initiating the actuation of said operating mechanism.

45 8. In a sewing machine having feeding means for advancing the work in a given direction, and stitch forming mechanism including a needle bar supported for reciprocatory movement toward and away from the work and for oscillatory movement transversely of the direction of reciprocatory movement, the combination of a continuously rotating shaft for reciprocating said bar, a cam shaft, a cam on said cam shaft for oscillating said bar, a cam on said cam shaft for controlling said feeding means, transmission means between said shafts, and means in engagement with the work for rendering said transmission means operative.

50 9. In a sewing machine having a work support, feeding means for advancing the work across said support, and stitch forming mechanism including a needle bar supported for reciprocatory movement toward and away from said support and for oscillatory movement transversely of the direction of reciprocatory movement, the combination of a continuously rotating shaft for reciprocating said bar, a cam shaft, a cam on said cam shaft for oscillating said bar, normally inoperative transmission means between said shafts, and trip mechanism associated with said work support and actuated by movement thereof relatively to said support for rendering said transmission means operative to drive said cam shaft.

55 10. In a sewing machine having a work support, feeding means for advancing the work across said support, and stitch forming mechanism including a needle bar supported for reciprocatory movement toward and away from said support and for oscillatory movement transversely of the direction of reciprocatory movement, the combination of a continuously rotating shaft for reciprocating said bar, a cam shaft, a cam on said cam shaft for varying the speed of said feeding means, normally inoperative transmission means between said shafts, and trip mechanism associated with said work support and actuated by movement thereof relatively to said support for rendering said transmission means operative to drive said cam shaft.

60 11. In a sewing machine having a work support, feeding means for advancing the work across said support, and stitch forming mechanism including a needle bar supported for reciprocatory movement toward and away from said work support and for oscillatory movement transversely of the direction of reciprocatory movement, the combination of a continuously rotating shaft for reciprocating said bar, a cam shaft, a cam on said cam shaft for oscillating said bar, normally inoperative transmission means between said shafts and including a ratchet wheel on said cam shaft, a reciprocating pawl actuated by said continuously rotating shaft and a detent for holding said pawl out of engagement with said ratchet wheel, and trip mechanism associated with said work support and actuated by movement away from said support for rendering said detent inoperative.

65 12. In a sewing machine, a continuously rotating shaft, an intermittently rotating cam shaft driven thereby, power transmitting means be-

5 tween said shafts including a ratchet wheel fixed on said cam shaft and a pawl actuated by said continuously rotating shaft and cooperating with said ratchet wheel to rotate said cam shaft, a 5 detent on said ratchet wheel for normally holding said pawl out of engagement therewith, and trip mechanism actuated by a variation in thickness of the work for rendering said detent inoperative.

10 13. In a sewing machine having feeding means for advancing the work, and stitch forming mechanism including a reciprocating needle bar, the combination of a continuously rotating shaft for reciprocating said bar and actuating said 15 feeding means, a cam shaft driven thereby, a speed varying device between said continuously rotating shaft and said feeding means, a cam on said cam shaft for automatically controlling said speed varying device, transmission means between said shafts, and means actuated by a variation in thickness of the work for rendering said transmission means operative.

14. In apparatus for advancing the work to 25 sewing machine stitch forming mechanism, the combination of an intermittently operated feed roll, a continuously rotating shaft, an eccentric radially adjustable on said shaft, a cam for effecting adjustment of said eccentric, normally inoperative transmission means for driving said 30 cam from said shaft, connecting means between said eccentric and said feed roll for intermittently operating said feed roll, and means actuated by a variation in the thickness of said work for rendering said transmission means operative.

35 15. In work feeding mechanism for a sewing machine, the combination of a feed roll, a radially adjustable, continuously rotating eccentric, connecting means between said eccentric and said feed roll for intermittently rotating said feed 40 roll, and means for automatically adjusting said eccentric in response to a variation in thickness of said work, including a cam, a continuously rotating member, transmission means between said member and said cam, and trip means in 45 yielding engagement with said work for rendering said transmission means operative.

16. In a sewing machine having a needle bar supported for reciprocatory movement toward and away from the work and for oscillatory movement transversely of the direction of reciprocatory movement, the combination of means for continuously reciprocating said bar, a rotatable cam for oscillating said bar, a ratchet wheel for intermittently rotating said cam, a reciprocating pawl for actuating said ratchet wheel, means for continuously reciprocating said pawl, a detent for holding said pawl out of engagement with said ratchet wheel, and means actuated by a variation in thickness of the work 60 for rendering said detent inoperative.

17. In a sewing machine having feeding means for intermittently advancing the work in a given direction, and stitch forming mechanism including a needle bar supported for longitudinal reciprocatory movement toward and away from the work and for oscillatory movement transversely of the direction of reciprocatory movement, the combination of means for continuously reciprocating said bar, and means for oscillating said 65 bar including a rotatable cam, a reciprocating member for rotating said cam, a detent for rendering said member inoperative to rotate said cam, and means contacting with said work and

actuated by a variation in thickness of said work for rendering said detent inoperative.

18. In mechanism for oscillating the needle bar of a sewing machine transversely of the direction of longitudinal reciprocatory movement, 5 the combination of a rotatable cam, a cam rod between said cam and said bar for oscillating said bar, a ratchet wheel for rotating said cam, a pawl for rotating said ratchet wheel, a detent for normally holding said pawl out of engagement with said ratchet wheel, and means for rendering said detent inoperative comprising a trip rod, a lever for actuating said trip rod, and a feeler contacting with the work to actuate said lever upon a variation in thickness of the 15 work.

19. In a sewing machine having a work support and a needle bar mounted to reciprocate toward and away from said support and to oscillate transversely of the direction of reciprocation, trip 20 mechanism for initiating the transverse oscillatory movement of the needle bar comprising a lever pivoted alongside said support, a feeler on said lever over said support, means for adjusting said feeler toward and away from said support, 25 and resilient means regulated by the adjustment of said feeler for resisting movement of said feeler away from said support.

20. In a sewing machine having a work support, feeding means for advancing the work across 30 said support, and adjustable means for varying the rate of feed of the work, trip mechanism for initiating the operation of said adjustable means comprising a rock shaft mounted alongside said support, a feeler extending from said rock shaft 35 over said support, adjustable means for resiliently resisting movement of said feeler away from said support, and adjustable means for limiting the movement of said feeler toward said support.

21. In a machine for sewing eyelet tape or the 40 like to successive lengths of fabric, the combination with stitch forming mechanism and work feeding mechanism of work supporting and guiding means comprising a bed plate having thereon an enclosed guide channel for a carrier tape 45 extending from the front end thereof to a point in advance of the stitch forming mechanism, the inner end of said channel communicating with the upper face of said bed plate, a guide member fixed to said bed plate and extending from front to rear thereof adjacent one edge of said guide channel, a retainer plate projecting from said guide member over said guide channel and spaced from said bed plate, a movable guide bar on said bed plate adjacent the opposite edge of said guide 50 channel, and a projection extending from said movable guide member over said guideway. 55

22. In a machine for sewing eyelet tape or the 60 like to successive lengths of fabric, the combination with stitch forming mechanism of work supporting and feeding mechanism including a bed plate having thereon a covered guide channel for a carrier tape extending from the front end thereof to a point in advance of the stitch forming mechanism, the inner end of said guide channel opening upwardly to the surface of said bed plate, a guide member for one edge of the fabric and the adjacent edge of the eyelet tape, a guide member for the opposite edge of the eyelet tape, and means 65 in the rear of said stitch forming mechanism for engaging said carrier tape to feed the same and for engaging with and feeding the work. 70

JOHN F. HAND.
